UNITED STATES PATENT OFFICE.

JAMES ALEXANDER MOORE, OF ATLANTA, GEORGIA.

SPRING FOR BEDS.

1,023,089.

Specification of Letters Patent.

Patented Apr. 9, 1912.

Application filed April 12, 1911. Serial No. 620,714.

To all whom it may concern:

Be it known that I, JAMES ALEXANDER MOORE, a citizen of the United States, residing in Atlanta, in the county of Fulton and State of Georgia, have invented a new and useful Spring for Beds, of which the following is a specification, reference being had to the accompanying drawing.

My invention relates to improvements in springs for beds.

Figure 1 is plan view of the construction. Fig. 2 is a perspective view of the medial supporting frame with the springs removed. Fig. 3 is a perspective view of the spring.

15 *a* refers to the lower extension of the coil and has for its object to provide a loop which is adapted to engage the slats *b b* as shown in Fig. 2.

20 *c* refers to that portion of the upper extension of the wire coil which is formed by a reverse turn of the wire, thereby providing a loop which is suitably arranged and adapted to engage one of the adjacent coils preferably on its left. *d* indicates that portion 25 of said wire which is bent in such manner as to form a loop; this however, is effected by drawing the same in a straight line for

a suitable distance and doubling it back to form a loop, it being then drawn in an oblique line to *e* which refers to the terminal 30 of the said wire which is suitably bent in such manner as to form a hook and adapted to engage its adjacent coil, or may be brought around in such manner as to engage its own coil.

35 The object of the several bends herein specified is to provide an interlocking mechanism which will enable the assembler to produce a structure with a web like surface without the use of other fastenings substantially as set forth.

40 What I claim and desire to secure by Letters Patent, is—

45 In an individual spring an upper coil structure comprising an open peripheral bend jointed to a closed offset loop *d* terminating in a hook *e* spaced from said loop substantially as shown and described.

In testimony whereof I have signed the foregoing specification.

JAMES ALEXANDER MOORE.

Witnesses:

J. PARNELL,
C. V. BARRY.
